[57] CLAIM

The ornamental design for an automobile body, as shown and described.

DESCRIPTION

FIG. 1 is a front, side perspective view of an automobile body;

FIG. 2 is a rear, opposite side perspective view of the automobile body shown in FIG. 1;

FIG. 3 is a side view of the automobile body shown in FIG. 1, it being understood that the side opposite to that shown is a mirror image thereof;

FIG. 4 is a front perspective view of the automobile body shown in FIG. 1; and,

FIG. 5 is a rear perspective view of the automobile body shown in FIG. 1.

The broken lines showing tires in FIGS. 1-3, and 5 are for illustrative purposes only and for form no part of the claimed design.
